SIGHT RIB FOR GUNS

Filed Aug. 27, 1925

FIG. 1.

FIG. 2.

FIG. 5.

FIG. 4.

FIG. 3.

Louis P. Smith Inventor

H. R. Bryant Attorney.

UNITED STATES PATENT OFFICE.

LOUIS P. SMITH, OF ITHACA, NEW YORK.

SIGHT RIB FOR GUNS.

Application filed August 27, 1925. Serial No. 52,898.

This invention relates to new and useful improvements in sight ribs for guns.

The primary object of the invention is to provide a top rib on a gun which is to be used 5 as a sighting plane and also as a truss to prevent the barrel from being bent downwardly.

A further object of the invention is to provide a structure for connecting the rib to the 10 gun barrel in such a manner as to permit a greater surface on the barrel to be ventilated or contracted by air for causing quick cooling of the barrel during rapid firing.

A still further object of the invention is to 15 prevent the rising of heat waves from the barrel to such an extent as to blur or interfere with the vision of the shooter.

And still another object of the invention is to provide such a connection between the 20 rib and the barrel that the heat from the barrel will be caused to be carried to the rib to cause the expansion and contraction of the barrel and rib to be practically the same, thereby preventing the barrel from buckling 25 or bending up or the rib from being torn loose from the barrel.

Other objects and advantages of the invention will be apparent during the course 30 of the following description.

In the accompanying drawing forming a part of this specification and in which like numerals are employed to designate like parts throughout the same,

Figure 1 is a side elevational view of the 35 gun barrel and rib embodying this invention;

Figure 2 is a top plan view of Fig. 1;

Figure 3 is an end elevational view of the muzzle end of the barrel and rib;

Figure 4 is a vertical sectional view taken 40 upon line IV—IV of Fig. 1, and

Figure 5 is a fragmentary longitudinal sectional view taken upon line V—V of Fig. 2.

In the drawing, wherein for the purpose 45 of illustration is shown a preferred embodiment of this invention, the numeral 5 designates the barrel portion of a gun which is of the choke type, being of less diameter at its muzzle end than at its breach end. Formed

with this barrel 5 is a top rib 6 which is 50 formed solid at its breach end 7 for approximately five inches and is then formed with a series of square or rectangular posts or uprights 8 which are equally spaced from each other for forming the transverse ventilating openings or air circulating passages 9 which permit substantially all of the outer surface of the barrel to be contacted by air for causing quick cooling of the said barrel during rapid firing. Figures 2 and 5 show 60 the top surface of the rib 6 transversely grooved, as at 10, in the manner shown.

The rib 6 is provided with a pair of suitably spaced beads 11 which permit the rib to be used as a sighting plane.

It will now be seen that the gun barrel 5 will be more quickly cooled during rapid firing than would be possible if the ventilating openings or air passages 9 were not provided. The rib will also act as a truss 70 for preventing the barrel 5 from being bent downwardly or away from the rib 6. It will, also, be seen that heat from the barrel 5 will radiate through the posts or uprights 8 for causing the rib 6 to be equally heated 75 to bring about substantially equal expansion and contraction of the barrel and rib, thereby preventing the barrel from buckling or bending or the rib from being torn loose from the barrel.

It is to be understood that the form of this invention herewith shown and described is to be taken as a preferred example of the same, and that various changes in the shape, size, and arrangement of parts may be resorted to 80 without departing from the spirit of the invention or the scope of the subjoined claim.

Having thus described the invention, I claim:

A gun barrel having a sighting rib integral 90 therewith and having supporting posts and intervening ventilating spaces of rectangular form, the said posts having transverse parallel sides, and being of uniform heat conducting capacity throughout their extent 95 transversely of the barrel.

In testimony whereof I affix my signature.

LOUIS P. SMITH.
